UNITED STATES PATENT OFFICE.

JOSEPH NORRIS AND NELSON MOORE, OF DUKE CENTRE, PENNSYLVANIA,
ASSIGNORS OF ONE-THIRD TO ALVIN H. LOW, OF SAME PLACE.

LOCKING STOP-COCK.

SPECIFICATION forming part of Letters Patent No. 288,725, dated November 20, 1883.

Application filed September 27, 1882. (No model.)

To all whom it may concern:

Be it known that we, JOSEPH NORRIS and NELSON MOORE, citizens of the United States of America, residing at Duke Centre, in the 5 county of McKean and State of Pennsylvania, have invented certain new and useful Improvements in Locking Stop-Cocks; and we do declare the following to be a full, clear, and exact description of the invention, such 10 as will enable others skilled in the art to which it appertains to make and use the same, reference being had to the accompanying drawings, and to the letters and figures of reference marked thereon, which form a part of this 15 specification.

The object of our invention is to construct a stop-cock which may be kept in a locked position, either open or closed.

Referring to the drawings, Figure 1 is a side 20 elevation of a stop-cock with our improvements attached. Fig. 2 is a longitudinal sectional view of the same, taken on line *x x* of Fig. 1. Fig. 3 is a section on line *y y* of Fig. 2. Figs. 4, 5, and 6 are details to be referred to.

25 A is the shell of the stop-cock, which is bored out, and a plug or core fitted thereto in the ordinary manner.

In the upper and inner end of the shell A is formed a groove, D, in which the projecting end of lock-bolt C slides when the said 30 end is released from the holes E in shell A, as will be hereinafter more fully set forth.

B represents a plug or core, which is recessed in its upper end at *a*, to receive the 35 locking parts of our device. In the recess is placed a series of tumblers formed of metal plates, *b*, having in one end a slot, *c*, into which is secured the end of spring *d*, its free 40 end bearing against the wall of the recess, as shown at *e* in Fig. 3.

Interposed between the tumblers *b* are the metal plates *f* with a slot, *h*, formed in one end to receive the pin *i*, cast upon the upper face of the lock-bolt C. Pin *k*, also cast upon 45 the face of the lock-bolt C, serves as a stop for the tumblers *b*, as shown in Fig. 3. The lock-bolt C also has a slot, *m*, through which protrudes the pin *l*, which is secured to the

floor of the recess *a*, and a spring, *n*, is secured to the lock-bolt, as shown in Fig. 4.

The operation of our device is as follows: Insert a key similar to the one shown in the head of the core in Figs. 1 and 2, the projection *o* in the floor of the recess *a* serving as a pivot on which the key turns. It will be readily seen, 55 when this is done, that a half-turn of the key to the right, working against the cam-face of lock-bolt C withdraws the projecting end of said lock-bolt from one of the series of holes E in the shell A far enough to allow the core 60 to be readily turned within the shell A in either direction. If the key be then turned another half-turn in the same direction—that is, to the right—the spring *n* operates upon the lock-bolt C, so that when the core is 65 moved in either direction the projecting end of the lock-bolt C on coming opposite either of the holes E in the shell A is forced into said hole, thereby locking core B and preventing its being turned further until the key 7c is again inserted and given a half-turn to withdraw the lock-bolt C, as before described.

We do not wish to confine ourselves to the peculiar mechanism constituting the lock herein described, but reserve the right to 75 modify the same; nor do we claim the construction of the lock illustrated in this application, but have thus particularly described and illustrated it as a practical lock to combine with the stop-cock. Any modification 80 of said lock contained in said recess by which the locking may be effected we consider as equivalent thereto.

The device may be operated with a single 85 hole, E, when it is only desired to lock the stop-cock closed; or, by adding another lock-bolt to the lock, it may serve in locking the stop-cock, either open or closed. We specify two or more holes, E, as being the most simple and desirable form. The location 90 of this hole or these holes E is to be regulated by the location of the bolt C, as all that is required of the hole or holes E is to engage the end of the lock-bolt C when the stop-cock is open or closed, as the case may be. 95

Having thus fully described our invention,

what we claim as new and useful, and desire to secure by Letters Patent, is—

A stop-cock having its core recessed to receive a lock, and having its shell provided with one or more holes on its inner side to receive the end of the lock-bolt, in combination with a locking device fitting into said recess in such a manner that when the end of the lock-bolt is inserted into one of said holes

the core will be locked to said shell until released by the application of a key, all substantially as specified.

JOSEPH NORRIS.
NELSON MOORE.
